UNITED STATES PATENT OFFICE.

PAUL H. BAUKOL, OF GRAND FORKS, NORTH DAKOTA.

WINDOW-SCREEN.

SPECIFICATION forming part of Letters Patent No. 567,370, dated September 8, 1896.

Application filed January 28, 1896. Serial No. 576,615. (No model.)

To all whom it may concern:

Be it known that I, PAUL H. BAUKOL, a citizen of the United States, residing at Grand Forks, in the county of Grand Forks and State 5 of North Dakota, have invented certain new and useful Improvements in Window-Screens; and I do declare the following to be a full, clear, and exact description of the invention, such as will enable others skilled in the art to 10 to which it appertains to make and use the same.

My invention relates to improvements in window-screens of that class or construction which is intended to permit flies or other insects to crawl from the inside out through an 15 aperture, but which prevents them from finding entrance to the inside; and the object is to construct a screen for the purposes mentioned which will serve all that is intended and which is durable in parts, easily and 20 cheaply made, and slightly in appearance.

I attain the purposes of my invention by means of the construction of parts and their assemblage in a common construction which I have illustrated in the accompanying drawings, forming a part of this specification, and 25 wherein—

Figure 1 is a view in perspective taken from the outer side of the screen and showing the complete device. Fig. 2 is a vertical section 30 taken on a line adjacent to the left-hand stile of Fig. 1. Fig. 3 is a detail of one of the inclined side pieces of the screen-frame. Fig. 4 is a detail view of a portion of the angular rail or bar. Fig. 5 is a view showing the spreader 35 and the blank from which it is constructed.

Referring to the drawings, A designates a suitable frame to which the screen or screens are connected or secured. This frame may be of any size suited to the window or door to 40 which it is fitted, and consists of the side pieces or stiles 12 and top and bottom rails 34. To the stiles are secured side pieces 5 5^X and 6 6^X, of similar construction, having their outer faces inclined, as seen at 7, from top to 45 bottom, and formed with seats 8 at their upper ends, in which the ends of the angular cross-bars are arranged and secured.

B designates the lower section of the screen, composed of a suitable wire-netting, the upper 50 end of which is turned about and secured on a metal cross-bar 9, substantially as shown in the drawings. This section B of the screen

is laid on the inclined side pieces 5 5^X, and secured in position by means of cleats or strips 10 10^X, fastened by nails or screws. 55

C designates a section of the screen made of wire-netting, and having at its lower end a metal cross-bar 11, bent at a suitable angle in cross-section, substantially as shown, the screen being turned up and partially down on 60 itself to a distance substantially the width of the cross-bar. At the top of the screen-section C is also a cross-bar 12, about which that end of the screen is folded and secured. This section is placed in position by laying it on 65 the side pieces 6 6^X, with its turned-up lower end 13 in the seats in the top of the nearest lower side pieces 5 5^X and 6 6^X, as seen in Fig. 2 of the drawings, and then fastening on the cleats or strips 14 14^X over the edges of the 70 wire-netting, the lower ends of the cleats being pushed down tight into the seats, with the netting and cross-piece about them, as seen in the drawings. This arrangement and disposition of the adjacently-disposed overlapped ends of the upper and lower ends of the screens form an opening between them having substantially parallel inclined surfaces, so that a fly or other insect crawling up 75 the screen will continue its travels through 80 the opening and land on the outside of the screen.

At the upper end of the upper section is secured a short strip of netting 15, closing the upper part of the opening in the frame, 85 and is provided in its lower end with an angular cross-bar 16, and having the end turned up and arranged in the seats formed in the upper ends of the upper side pieces 6 6^X, and secured therein by means of short strips or 90 cleats 17 17^X, having the ends pushed snugly down in the bend of the netting, substantially as shown. This arrangement of the parts affords the upper opening of the screen, through which the insects find exit into the outer air. 95 To prevent the adjacently-arranged cross-bars from being bent or displaced, I arrange a bracing piece or plug 18 between them, as shown. This brace or plug 18 is made out of a piece of sheet metal cut into the shape of a cross, and then striking down the two shorter arms parallel with each other to adapt them to be inserted between the meeting rails and bending the other arms to lie over and against 100

the opposite faces of the two rails or cross-bars, substantially as shown in the drawings.

Having thus described my invention, what I claim, and desire to secure by Letters Patent, is—

1. A window-screen, comprising a suitable rectangular frame, side pieces secured to the stiles of the frame, having their outer faces inclined from top to bottom and formed with seats in their upper ends, a wire-netting having a cross-bar in its upper end secured on the lower inclined side pieces, wire-nettings secured to the inclined side pieces, each having a metal cross-bar secured to its upper end and a metal cross-bar bent angular in cross-section, secured to its lower end and disposed and secured in the seats in the upper ends of the nearest lower side pieces, and a short section of netting to close the upper end of the frame, provided with a cross-bar angular in cross-section disposed in the seats in the upper ends of the upper side pieces, substantially as and for the purposes specified.

2. A window-screen, comprising a suitable frame, side pieces secured to the stiles of the frame, having their outer faces inclined from top to bottom and formed with seats in their

upper ends, a wire-netting having a metal cross-bar in its upper end, secured to the lower inclined side pieces, a wire-netting secured to the inclined side pieces and having a metal cross-bar in its upper end, and its lower end turned up and bent over and a metal cross-bar angular in cross-section secured in the bent-up portion, which cross-bar and bent-up portion are disposed in the seats in the ends of the nearest lower side pieces, a short section of wire-netting to close the upper end of the frame, a cross-bar angular in cross-section on the lower end of the short screen-section and disposed in the seats of the upper set of inclined side pieces, and staying-pieces between the adjacently meeting rails or cross-pieces of the screens comprising central plugs to set between the rails and extensions to reach over and against the outer sides of the rails, substantially as described.

In testimony whereof I hereunto affix my signature in presence of two witnesses.

PAUL H. BAUKOL.
